LAPEL PIN OR SIMILAR ARTICLE

Charles W. Lapham, Los Angeles County, Calif.
(2743 W. 15th St., Los Angeles, Calif. 90006)

Filed July 21, 1965, Ser. No. 86,239

Term of patent 14 years

(Cl. D45—19)

FIG. 3.

FIG. 1 is a front elevational view of the lapel pin or similar article embodying my new design;

FIG. 2 is a rear elevational view thereof; and

FIG. 3 is a top plan view thereof.

I claim:

The ornamental design for a lapel pin or similar article, as shown.
